UNITED STATES PATENT OFFICE.

NELSON H. SEELYE, OF WINCHESTER, MASSACHUSETTS.

RECIPROCATING-BEAM MACHINE.

SPECIFICATION forming part of Letters Patent No. 707,168, dated August 19, 1902.

Application filed September 20, 1901. Serial No. 75,734. (No model.)

To all whom it may concern:

Be it known that I, NELSON H. SEELYE, of Winchester, in the county of Middlesex and State of Massachusetts, have invented an Improved Reciprocating-Beam Machine, of which the following is a specification, reference being had to the accompanying drawings, in which—

Figure 1 is a rear elevation of one of my improved beam-machines. Fig. 2 is an end elevation from the right of Fig. 1. Fig. 3 shows some of the parts in section on a larger scale, and Fig. 4 is a plan of the end of the beam.

Beam-machines used mainly for cutting leather and other sheet material and comprising a bed, a beam, and mechanism for reciprocating the beam have long been on the market, the office of the beam being to force the cutting-tools through the leather or other material. In some of these machines the cutting-tools are arranged by hand on the leather and forced through the leather by the pressure of the beam, the leather being supported by a cutting-block on the bed. In others the cutting-tool is a knife which reciprocates with the beam, while in others the beam and bed are provided with punch and die cutters, all of which will be plain to all skilled in the art without further description. Moreover, for a large class of work it is necessary that the beam should be intermittent in its operation—that is, it should be set in operation by a treadle and should stop automatically as it completes its stroke away from the bed unless the pressure on the treadle be continued—and a variety of mechanisms have long been known for accomplishing this result. My invention relates to this class of machines; and it consists in certain features which are fully described below, all aiding in making a machine of this class much more efficient and much better adapted to withstand the severe strains to which this class of machines are subjected.

One feature of my invention relates to means for connecting the belt-wheel H with and disconnecting it from the actuating-shaft of the beam, and consists in a shipping-lever G, fulcrumed near its middle, with its lower arm connected in the usual way with one member G of a friction-clutch, and also con-

nected at its lower end to the actuating-treadle g⁷, which is depressed by the attendant when he desires to engage the members 55 of the friction-clutch, which are the spider G and the belt-wheel H, and with its upper end in the path of cam g⁸, carried by the beam, all as most clearly shown in Fig. 3. It is of prime importance in machines of this class, as 60 has long been known, that the labor of the attendant in depressing treadle g⁷ against the force of its spring g⁸ be reduced to the minimum, and to that end I have devised this combination of shipping-lever with its upper 65 end disposed in the path of cam g⁸, carried by beam A, and its lower end connected to the treadle g⁷, for it is by means of this combination that I am enabled with a close adjustment of belt-wheel H and spider G, obtained as hereinafter described, to greatly 70 lighten the labor of the operator in bringing the clutch members G and H into working contact and also reduce to the minimum the slipping of the moving clutch member H on 75 the normally stationary clutch member G, for by a very few degrees of depression of treadle g⁷, and thereby rocking shaft g⁶ accordingly, arm g⁵ of rock-shaft g⁶ moves link g⁴, straightens toggle-arms g¹ g², and thereby 80 forces the lower end of lever G outward and presses member G firmly against belt-wheel H, and at the same time carries the upper end of lever G into the path of cam g⁸ as the beam A descends. This feature of my invention depends for its perfect working upon the nicety 85 of adjustment between the members G and H of the friction-clutch, and a second feature of my invention relates to that adjustment and consists in providing a bushing h for belt-wheel H, which bushing is adjusted by means of screw-stud h¹, nut h², and cap h³, and is held after adjustment by set-screw h⁴. Nut h⁵ is a check-nut, and stud h¹ is of course fast in 90 the end of the shaft. The adjustment of belt-wheel H is readily effected by slackening set-screw h⁴ and check-nut h⁵ and turning nut h² until bushing h will hold belt-wheel H with its inner face as close to the outer face of spider G as possible, in view of the fact that 100 wheel H must revolve clear of spider G until lever G is moved to force the friction-surface of spider G into firm contact with the corresponding surface of wheel H.

A third feature of my invention relates to insuring great pressure attained with the maximum quickness and minimum motion of the treadle g^7 between spider G and wheel 5 H, and consists in the combination of spider G with treadle g^7 by means of toggle-arms g^1 g^2 , link g^4 , and a rock-shaft g^6 , rocked by treadle g^7 , and having an arm g^5 connected to link g^4 . The result is that the friction-10 surfaces of the spider G and belt-wheel H are forced together with the maximum pressure by the minimum effort of the attendant, and in view of the fact that the attendant is required to do this not less than one thousand 15 times per day on the average its importance will be plain.

The brake mechanism g^9 g^{10} and the hand-wheel J for adjusting the bed are too well known to require description.

20 What I claim as my invention is—

1. In combination a beam; a driving-shaft; means connecting the shaft and beam; a power-driven wheel loose on the shaft; a clutch with one member fast to the power-driven wheel and the other member splined 25 on the shaft; a shipping-lever fulcrumed near its middle and connected by its lower arm with the latter clutch member; a treadle connected with the lower end of the shipping-lever; and a cam carried by the beam and operating on the upper end of the shipping-lever; all substantially as described.

2. In combination a shaft; a beam; means

connecting the shaft and beam; a sleeve on the shaft; means for fastening the sleeve to 35 the shaft with provision for longitudinal adjustment of the sleeve on the shaft; a power-driven wheel loose on that sleeve; a clutch member fast to the power-driven wheel; a second clutch member splined on the shaft; 40 a rock-shaft; a treadle for rocking it against the force of a spring; that spring; and means for connecting the rock-shaft with the second clutch member; all substantially as described. 45

3. In combination a beam; a driving-shaft; means connecting the shaft and beam; a power-driven wheel loose on the shaft; a clutch with one member fast to the power-driven wheel and the other member splined 50 on the shaft; a shipping-lever fulcrumed near its middle and connected by its lower arm with the latter clutch member; toggle-arms, one connected at its outer end with the lower end of the shipping-lever, the other connected 55 at its outer end with a fixed support, and both connected at their inner ends with a link; that link connected at its upper end with the toggle-arms and at its lower end to one arm of a rock-shaft; that rock-shaft; a treadle 60 for rocking it; and a treadle-spring on that treadle; all substantially as described.

NELSON H. SEELYE.
